DESIGN FOR A MOTOR VEHICLE VENTILATOR

Ralph F. Peo, Buffalo, N. Y., assignor to Houde
Engineering Corporation, Buffalo, N. Y., a cor-
poration of New York

Application May 18, 1935, Serial No. 56,900

Term of patent 7 years

To all whom it may concern:

Be it known that I, Ralph F. Peo, a citizen of the United States and a resident of the city of Buffalo, in the county of Erie and State of New York, have invented a new, original, and ornamental Design for a Motor Vehicle Ventilator, of which the following is the specification, reference being had to the accompanying drawing, forming a part thereof.

On the drawing:

Figure 1 is a perspective view of the motor vehicle ventilator, showing the deflector thereof in its open position;

Figure 2 is a plan view of the motor vehicle ventilator with the deflector in its closed position; and

Figure 3 is a sectional view taken on the line III—III of Figure 1, showing the transverse contour of the motor vehicle ventilator and the deflector in its closed position.

I claim:

The ornamental design for a motor vehicle ventilator substantially as shown and described.

RALPH F. PEO.
